No. 885,769.

PATENTED APR. 28, 1908.

A. A. LOW & H. HERTZBERG.
ELEMENT FOR ELECTRIC HEATERS.
APPLICATION FILED MAY 4, 1907.

UNITED STATES PATENT OFFICE.

ABBOT A. LOW, OF HORSESHOE, AND HARRY HERTZBERG, OF NEW YORK, N. Y.; SAID HERTZBERG ASSIGNOR TO SAID LOW.

ELEMENT FOR ELECTRIC HEATERS.

No. 885,769.

Specification of Letters Patent. Patented April 28, 1908.

Application filed May 4, 1907. Serial No. 371,874.

To all whom it may concern:

Be it known that we, ABBOT AUGUSTUS Low and HARRY HERTZBERG, citizens of the United States, residing at Horseshoe, St. 5 Lawrence county, State of New York, and the city of New York, borough of Brooklyn, county of Kings, and State of New York, respectively, have invented a certain new and useful Element for Electric Heaters, of 10 which the following is a specification.

This invention is an element for electric heaters, and the object in view is to overcome the tendency of a carbon resistance to flake or chip under the heat developed therein by 15 an electrical current.

It is well known to those skilled in the art that a solid piece or block of carbon when heated by an electric current will, after a comparatively short time, deteriorate to such an 20 extent as to seriously impair its efficiency.

To overcome the foregoing objections, and to attain the objects of this invention, we provide a heater - element composed of a plurality of sections held together and in 25 electrical contact by suitable means, such as a core of insulating material composed of one or more asbestos cords or strands.

In the accompanying drawings, we have 30 illustrated one practical embodiment of the invention, but the construction shown therein is to be understood as illustrative only, and not as defining the limits of the invention.

Figure 1 is a side elevation of a heater- 35 element or unit embodying this invention. Fig. 2 is a longitudinal section on the line 2—2 of Fig. 1. Fig. 3 is a cross section on the line 3—3 of Fig. 1. Fig. 4 is a side view illustrating another embodiment of the in- 40 vention. Fig. 5 is an end view of Fig. 4. Figs. 6 and 7 are side and end views, respectively, of another form of heater - element. Fig. 8 is a longitudinal section through an- 45 other form of the heater-element.

In the construction shown in Figs. 1, 2 and 3 of the drawings we have represented a heater-element or unit, A, composed of members, B, and an insulating core, C, C'. Each member, B, is a piece of electrical resistance 50 material, preferably a molded block of carbon. The blocks forming the members of the heater unit may be of any suitable shape and size, as for example, each block may be of the square form shown in Figs. 3 and 4, or 55 they may be of the cylindrical form shown in

Fig. 7, or they may be of any other desired cross section. As shown in said Figs. 1, 2 and 3, the blocks, B, are provided with a plurality of openings, b, and through these openings are passed the cords forming the core, C, C', whereby the members are threaded on said core. Each core consists of a suitable insulating material, such as a cord composed of asbestos or other appropriate substance. The cords operate to hold or confine the carbon blocks, B, in electrical contact one with the other, and it is preferred to confine said blocks in such close contact as to obviate the formation of spark gaps between the members when an electric current is passed through the resistance or heater unit. The cords may be provided with any suitable means for holding the blocks against sliding movement, but as shown in the drawings, we employ metallic terminal plates, D, adapted to be fastened in any suitable way on the cord or cords, C, C', whereby provision is made for the attachment of the wires, E, E', of an electric circuit.

The construction of the element or unit 80 shown in Fig. 4 is quite similar to that heretofore described. A suitable number of molded blocks, B', are employed, each block having a single opening, b'. It is evident that the blocks may be square, round or 85 other desired cross section, and that the blocks are assembled to receive a single core, C', composed of asbestos or other appropriate insulating material. The cord is shown as having metallic terminals, D', to 90 which are connected the electric conductors.

In the form of the heater element shown in Fig. 8 of the drawings, we employ the series of members B² on the core C², in connection with the metallic terminals to which the 95 leading wires are attached. Said element is, however, adapted to be doubled so as to assume the shape, substantially, of the letter U, and it is incased by suitable incasing material, indicated at F. This incasing ma- 100 terial is preferably of a heat-absorbing nature, and it is molded around the element so as to form a part thereof.

Having thus fully described the invention, what we claim as new, and desire to secure 105 by Letters Patent is:

1. An element for electrical heaters comprising a plurality of perforated blocks each composed of molded carbonaceous material, said blocks being assembled with their faces 110

in direct engagement with each other, a core composed of a strand of non-combustible material which extends through said perforations of the blocks, and metallic terminal 5 members secured on said core and engaging with the end blocks of the series of blocks for clamping the latter in contact firmly with each other.

2. An element for electrical heaters comprising a series of perforated molded blocks composed of resistance material, each of said blocks having a plurality of openings, a plurality of parallel strands composed of electrical insulating and non-combustible material, said strands extending through the openings of said blocks, and metallic terminal members each secured on said strands and engaging the end blocks of the series of blocks, said terminal members clamping 20 the series of blocks firmly in contact with each other.

3. An element for electrical heaters comprising a pliable core composed of a strand of non-combustible and insulating material,

a series of members composed of resistance 25 material and threaded on said core, metallic terminal members secured on the core and operating to exert pressure on the members for clamping the latter in direct engagement, and a mass of heat absorbing material in 30 casing said members and the core.

4. An element for electrical heaters comprising a core of insulating and non-combustible material, blocks composed of resistance material and threaded on said core, 35 metallic terminal members adapted to clamp said blocks into engagement with each other, and a mass of molded heat absorbing material permanently incasing said members.

In testimony whereof we have signed our 40 names to this specification in the presence of two subscribing witnesses.

ABBOT A. LOW.
HARRY HERTZBERG.
